UNITED STATES PATENT OFFICE.

WILLIAM A. ELLIS AND THOMAS ELLIS, OF PHILADELPHIA, PA.

IMPROVEMENT IN OPERATING THE TEMPERING-WHEELS OF CLAY-PITS.

Specification forming part of Letters Patent No. 178,126, dated May 30, 1876; application filed May 2, 1876.

To all whom it may concern:

Be it known that we, WILLIAM A. ELLIS and THOMAS ELLIS, of Philadelphia, Pennsylvania, have invented certain Improvements in Operating the Tempering-Wheels of Clay-Pits, of which the following is a specification:

The object of our invention is to provide efficient, direct, and economical driving mechanism for clay and other like mills; and this object we attain in the manner which we will now proceed to describe, reference being had to the accompanying drawing, in which—

Figure 1 is a plan view of a clay-tempering pit with our improvement, and Fig. 2 a vertical section of the same, drawn to an enlarged scale.

A is the pit, and B the usual radial arm, adapted to a pin, *a*, on a central standard in the pit, and carrying the wheel D, the rotation of which in the pit causes the tempering of the clay in the usual manner.

The rotation of the radial arm and its wheel is usually effected either by means of horse-power applied to the outer end of the arm, or by means of a suitable gearing driven by a stationary engine properly located.

There are well-known objections to these plans, which we overcome in the following manner: Around the edge of the pit we lay a circular track, *b*, to which is adapted a loco-

motive, E, of suitable construction, this locomotive being connected by a link to the end of the arm B. We prefer to so arrange the axles of the locomotive radially that they shall converge toward the central pin *a*, and to make the outer wheels of said locomotive larger in diameter than the inner wheels.

A locomotive thus constructed will run with ease on a circular track of comparatively small diameter; but it should be understood that we do not restrict ourselves to a locomotive having axles thus arranged, as one with parallel axles will serve the desired purpose if the track be sufficiently large in diameter, or a three-wheeled locomotive may be used.

We claim as our invention—

The combination of a clay or other like mill, having a radial arm, B, a circular track, and a locomotive adapted to the track and constructed for attachment to the arm, all substantially as set forth.

In testimony whereof we have signed our names to this specification in the presence of two subscribing witnesses.

WM. A. ELLIS.
THOS. ELLIS.
